UNITED STATES PATENT OFFICE.

GEORGE STAHL, OF DAYTON, OHIO, ASSIGNOR OF ONE-THIRD TO
WILLIAM P. COFFMAN AND ONE-THIRD TO JOHN I. COFFMAN,
OF DAYTON, OHIO.

FRICITION-CLUTCH.

No. 820,446.

Specification of Letters Patent.

Patented May 15, 1906.

Application filed December 14, 1904. Serial No. 236,783.

To all whom it may concern:

Be it known that I, GEORGE STAHL, a citizen of the United States, residing at Dayton, in the county of Montgomery and State of 5 Ohio, have invented certain new and useful Improvements in Friction-Clutches, of which the following is a specification.

My invention relates to improvements in friction-clutches; and the object of the invention is to provide a simple and effective friction-clutch adapted for use with any form of power-driven machinery, particularly lathes, shaping-machines, and devices of that character where it is desired to start and stop the 15 machinery quickly.

My invention consists in the constructions and combinations of parts hereinafter described, and set forth in the claims.

In the accompanying drawings, Figure 1 is 20 a side view of a device embodying my invention. Fig. 2 is a partial sectional view of the same. Fig. 3 is a side elevation of some of the operating parts removed. Fig. 4 is a side view showing parts somewhat modified from 25 those shown in Fig. 1 and in reverse order. Fig. 5 is a detail view in perspective, showing the construction of some of the operating parts.

Like parts are represented by similar letters of reference in the several views.

In carrying out my invention I employ an outer power-driven wheel or pulley *a*, which is mounted in a well-known manner to turn loosely on a shaft *a'*. The outer periphery of 35 this wheel *a* may be in the nature of a pulley or band-wheel or adapted to be driven in any well-known manner. It is preferably provided with an inner hub *a²* and a suitable number of arms *a³*, which connect the outer 40 rim to said hub. This hub and the arms are preferably offset slightly from the center of the rim, and the rim is turned out at one side, as shown in Fig. 2, to receive the inner friction device *b*. This consists of an outer rim *b'* and an inner hub *b²*, connected by a suitable number of arms *b³*. These parts—that is, the rim, hubs, and arms—are preferably cast integrally, and the outer rim is split 45 transversely, as shown at *b⁴*, adjacent to each 50 of the arms, and from this cross-slot there extends a circumferential slot *b⁵*, which extends through the rim, leaving a projecting portion *b⁶*, which extends from a point near the hub-

arms for a distance equal to the length of the longitudinal slot *b⁵*. This projecting portion 55 *b⁶* is formed at its extremity with an inwardly-extending lug *b⁸*.

That portion of the rim which lies adjacent to the arm *b³* or on the opposite side of the slot *b⁴* is also provided with an inwardly-projecting lug *b⁷*, and between these lugs there is formed a depression or socket *b⁹* in front of the hub-arm *b³*. Within this depression or socket there is pivoted an operating-arm *c*. This arm is cam-shaped at its outer end and 65 fits between the projections *b⁷* and *b⁸* and is adapted as the arm is moved to force the free portions of the friction device outwardly, so as to contact with the inner periphery of the outer rim *a*. The operating-arms *c* are curved 70 in the direction of the periphery of the rim and thence inwardly, so as to stand opposite the main shaft *a'*, the friction device *b* being secured to said shaft. The inner ends of the operating-arms *c* are provided with adjustable contacting parts *c'*, adapted to be engaged by a cone-shaped hub or collar *c²*, which may be forced between these contacting parts, and thus move the arms outwardly 75 sufficient to cause the free portions of the inner friction device to impinge against the inner periphery of the outer wheel or pulley. 80

It will be seen that when the conical collar *c²* is forced between the operating-arms they will be moved outwardly and cause the free 85 parts of the clutch device to contact with the periphery and firmly engage it, causing the pulley and shaft to revolve together. When the collar is moved from those arms, the resiliency of those parts will cause them to resume 90 their normal positions, and thus free said pulley. The adjustable contacting devices in the ends of the operating-arms permit the same to be adjusted so as to secure the proper degree of pressure on the impinging parts. 95

In Fig. 1 I have shown two arms, and consequently a duplicate set of impinging parts. In Fig. 4 I have shown four such parts. Any suitable number may be employed. 100

Having thus described my invention, I claim—

1. The combination with the outer revolving part of an inner friction device consisting of a rim split transversely and circumferentially as set forth and means for forcing the 105

parts on each side of said transverse slot in opposite directions to cause them to impinge the outer revolving part, substantially as described.

5. 2. The combination with the wheel or pulley, of the inner friction device having a rim split transversely in one or more places and having a circumferential slot extending to a point adjacent to where said rim is split transversely, a depression or socket between the free ends of the rim-sections formed by said longitudinal slot, and a pivoted lever located in said depression, and means for operating said lever, substantially as and for the purpose set forth.

20. 3. In a friction device, an outer clutch member, an inner clutch member within the periphery of said outer clutch member, the periphery of said inner clutch member being divided by transverse slots into a plurality of segments, a tongue formed on each of said segments by the intersection of a circumferential slot in each segment with one of said transverse slots, and means for forcing said 25 tongues outward to frictionally engage said outer clutch member, substantially as specified.

130. 4. The combination with the outer wheel or pulley having a hub offset as set forth, of an inner device located within said wheel consisting of a rim split transversely and circumferentially, pivoted operating-arms to engage

the rim-sections formed by said transverse and longitudinal splitting, and a sliding member adapted to contact with the inner ends of 35 said operating-levers as set forth.

5. The combination with the outer pulley or wheel, of an inner friction device having a transversely-split rim, operating-arms adapted to move the sections of said rim on each 40 side of said split, said operating-arms extending inwardly and provided with adjustable contacting devices, and a sliding member adapted to engage with said contacting devices, as and for the purpose specified. 45

6. The combination with a shaft and pulley turning loosely thereon, a friction device secured to said shaft consisting of a rim fitting within the rim of said pulley and split transversely and circumferentially, operating- 50 arms to engage the sections of said rim on each side of said split, adjustable contacting devices in the ends of said arm, and a movable member on said shaft adapted to be moved to and from said arms and contact 55 with the same, substantially as and for the purpose specified.

In testimony whereof I have hereunto set my hand this 9th day of December, A. D. 1904.

GEORGE STAHL.
